UNITED STATES PATENT OFFICE.

LINDSLEY SCHEPMOES, OF HASBROUCK HEIGHTS, NEW JERSEY, ASSIGNOR TO THE SAFETY CAR HEATING & LIGHTING COMPANY, A CORPORATION OF NEW JERSEY.

SUPPORTING-BRACKET FOR LAMPS.

1,231,947.

Specification of Letters Patent.

Patented July 3, 1917.

Application filed September 30, 1915. Serial No. 53,247.

To all whom it may concern:

Be it known that I, LINDSLEY SCHEPMOES, a citizen of the United States, residing at Hasbrouck Heights, in the county of Bergen and State of New Jersey, have invented a new and useful Improvement in Supporting-Brackets for Lamps, of which the following is a specification.

This invention relates to railway vehicles and, particularly, to novel means for supporting the light-fixtures and other associated parts.

Among the objects of my invention may be noted the following: to provide a simple, cheap, strong and inexpensive means, adapted to the modern railway-cars, for supporting light-fixtures and coöperating and associated parts, without strain upon or injury to the ceiling or roof-structure of said vehicles; to provide means by which the light-fixture and socket-support may be independently and detachably secured to a common support, so as to enable said members to be carried without strain upon the car ceiling; and to provide a simple and effective structure wherein the socket-support, light-fixture and junction-box can be associated by independent means enabling installation, inspection and repair to be conducted easily, quickly and effectively.

With the above objects in view, and others which will be detailed during the course of this description, my invention consists in the parts, features, elements and combinations thereof hereinafter described and claimed.

In order that my invention may be clearly understood, I have provided drawings wherein:

Figure 1 is a vertical, longitudinal section of the roof of a car, taken on the line 1—1 of Fig. 2, showing features of construction embodying my invention, the view being curtailed by breaking the same at several points;

Fig. 2 is a bottom-plan view of Fig. 1, taken substantially on the line 2—2 of Fig. 1.

Fig. 3 is a sectional detail taken substantially on the line 3—3 of Fig. 2;

Fig. 4 is a sectional detail substantially on the line 4—4 of Fig. 1;

Fig. 5 shows a form of my invention in

sectional elevation of certain details, differing from the form thereof shown in Fig. 1; and

Fig. 6 is a sectional elevation of a form of my invention in the matter of certain details, differing from the form thereof shown in Fig. 1.

Referring to the drawings, and particularly Figs. 1 and 2, the numeral 1 indicates the roof of the car, 2 the ceiling and 3 the carlines, the latter being shown as substantially U-shaped in cross-section and arranged so as to enable the closed sides 4 thereof to be utilized as a sustaining means for the supporting-plate 5, the opposite ends 6 of which are upturned at an angle to the base thereof so as to coöperate with the closed sides of the carlines, through which latter and the said upturned ends 6 a headed bolt 7 is passed whereby to secure the parts rigidly together, as by jam and checknuts 8. By this means, the supporting-plate 5 is rigidly held in place so as to relieve the car ceiling of all strain, resulting from heavy fixtures depending therefrom, and such strain is thrown upon the roof-structure, which is strong and rigid and which is given its support by the usual means, including the car-lines 3 and the furring 3a.

The ornamental casing or frame of the light-fixture is shown at 9 and is removably secured to the supporting-plate 5 by screws 10, passing through lugs 11, secured to a suitable portion of the frame 9, and passing through the ceiling 2, and threaded into the supporting-plate 5, any number of said screws 10 being employed as may be found necessary or desirable, four being shown in the present instance, see Fig. 2. Thus the light-fixture is held firmly against the ceiling and no strain is imposed upon the latter. The socket-support or tube 12 depends centrally within the fixture 9, and extends through the ceiling 2 and the supporting-plate 5, and is threaded into a nipple 13, of a plate 14, secured by means of screws 15 to the bottom of the junction-box 16, the bottom of which is provided with an opening 100 closed, in great measure, by the plate 14, and through which opening and the center of the plate and the tube 12 the leads to the sockets of the particular light-cluster are extended.

from the cable or group of leads which are passed through and housed within the conduit 17, joined to the opposite ends of the junction-box 16. Preferably, at the point 5 where the junction-box is connected to the supporting-plate 5, the latter and the ceiling are apertured so as to enable the screws 15 and nipple-plate 14 to be readily placed and removed. The junction-box, see Figs. 2 and 3, is connected to the supporting-plate 5, by means of ears 18, and screws or short bolts 19, two being found to be sufficient for the purpose, and said ears extending from the opposite sides of the junction-box substantially at a right-angle to the conduits 17.

Viewing Fig. 3, it will be seen that the lugs 11, through which the screws 10 pass, are provided with a bore of two different dimensions, the lower portion of the bore being adapted to receive the head 20 of the screw 10 and the upper portion of the bore being adapted to receive the body of the screw 10, while the shoulder 21, between the two bore-portions, is adapted to be engaged by a spring lock-washer 22, forced thereagainst by the head of the screw 10. Thus, when the screw is passed upwardly through the lug 11 and into the supporting-plate 5, its head will tightly clamp the lock-washer 22 against the shoulder 21, so that the spring quality of the washer will be utilized to frictionally hold the screw from turning in the plate 5. The light-fixture is thus firmly held in place against the ceiling and prevented from shaking loose under the shocks and jars resulting from the running of the car. This structure is of importance in my invention since it involves the several valuable practical functions above noted and, at the same time, constitutes the sole detachable support for the light-fixture when combined with the supporting-plate, and is independent of the supporting means for socket-support. It will be understood that, while I have shown herein screws and coöperating parts of special form for my purposes, and which have been found effective and sufficient, I do not wish to be limited to the details of construction shown, since several changes in details can be made without departing from either the spirit or principle of my invention, and involving only mechanical skill. In other words, the importance of this feature of my invention resides in the fact that it is a sufficient and effective fastening and support for the light-fixture when combined with the supporting-plate in any suitable manner and relieves the ceiling of all strain or stress which might be imposed thereon if any part of the connecting and supporting means were applied to the ceiling of the car in any manner whatever.

Viewing Fig. 4, it will be seen that the ex-

slotted vertically for the passage of the conduits 17; and, upon viewing Fig. 6, it will be seen that the carlines 3 may be extended downwardly considerably, as indicated by 3^x, so as to enable the ceiling of the car to rest thereagainst, or be secured thereto, as a brace and support. In this form of my invention, the conduits 17 will pass through the carline, as clearly indicated at 24, and the supporting beams 3^a are discarded.

In Fig. 5, I have shown another form of my invention for securing the tube 12 in position and, therein, it will be seen that the nipple-plate 14^a is secured directly against the ceiling 2 by means of the screws 15^a passing through the plate and the ceiling, and threaded into the supporting-plate 5. In this form of my invention, the supporting-plate becomes the holding medium for the tube 12 and parts supported thereby, and the junction-box is in no manner interfered with, or tapped for the purpose.

From the foregoing, it will be seen that the junction-box is detachably secured to the supporting-plate 5 by the means 18 and 19; that the light-fixture is detachably secured to the supporting-plate 5 by the means 10 and 11; and that the socket-support 12 is detachably secured to the supporting-plate indirectly, Fig. 1, by the nipple-plate 14 and screws 15 entering the bottom of the junction-box, and directly, in Fig. 5, by the nipple-plate 14^a and screws 15^a passing through the ceiling into said plate. All of these means for securing the respective parts to the supporting-plate 5 are independent the one of the others, and, thereby, the very desirable advantages are secured of enabling installations to be made without hindrance or interference with the light-fixture and socket-support, and permitting the removal of the socket-support and light-fixtures for inspection and repairs. Moreover, the light-fixture can be removed without compelling the removal of the socket-support.

Having thus described my invention, what I claim and desire to secure by Letters Patent is:

1. In combination with the carlines of a vehicle, a supporting-plate connected thereto, a junction-box connected to the plate above the same, an ornamental fixture removably secured to the plate, a lead-tube extending within the fixture and through the plate, and means holding said tube in coöperative relation to the junction-box.

2. In combination with the carlines of a vehicle, a supporting-plate connected to said carlines and provided with an aperture therein, a junction-box supported on the plate and having an aperture in the bottom thereof registering with the aperture in the plate, conduits secured to the junction-box and passing through the supporting-plate,

a lead-tube arranged in coöperative relation to the said two apertures, a nipple-plate connected to the lead-tube, and means for supporting the nipple-plate in place.

5 3. In combination with the roof of a vehicle, a supporting-plate and means for securing the same to said roof; a junction-box supported on said supporting-plate; a

fixture casing supported on said supporting-plate; a socket-support supported on said plate; and a plurality of independent means detachably securing the junction-box, fixture-casing and socket-support to said supporting-plate. 10

LINDSLEY SCHEPMOES.
